UNITED STATES PATENT OFFICE.

FRANCIS R. GOOD, OF PHILADELPHIA, PENNSYLVANIA, ASSIGNOR OF ONE-HALF TO
JOHN E. VOLLMER, OF LONG BEACH, CALIFORNIA.

RULING-PEN.

1,213,095.

Specification of Letters Patent. Patented Jan. 16, 1917.

Application filed March 15, 1916. Serial No. 84,334.

To all whom it may concern:

Be it known that I, FRANCIS RAYMOND GOOD, a citizen of the United States, residing at Philadelphia, in the county of Philadelphia, State of Pennsylvania, have invented 5 new and useful Improvements in Ruling-Pens, of which the following is a specification.

This invention relates to a ruling pen, and 10 pertains especially to a ruling pen such as is used by draftsmen.

It is an object of this invention to provide 15 a ruling pen with means for adjusting the nibs and by which delicate and sensitive adjustments may be made.

It is another object of this invention to provide means for adjusting the nibs adapted to be used with indicia on the handle of the pen to indicate the distance 20 between the nibs.

It is a further object of my invention to provide a ruling pen with means mounted on the shank of the handle whereby the distance between the pen nibs may be adjusted. 25

My invention further consists of features of design and assemblage of the parts of a ruling pen, whereby simplicity of structure and ease of adjustment are secured.

30 I have illustrated an embodiment of my invention in the accompanying drawing, in which:

Figure 1 is an elevation of my improved pen. Fig. 2 is a vertical section thereof 35 with the nibs broken away. Fig. 3 is an enlarged section as seen on the line 3—3 of Fig. 2. Fig. 4 is an enlarged fragmentary detail of the slide and collar connection. Fig. 5 is an enlarged side view of a detail 40 showing the connection between the shank and nibs. Fig. 6 is a vertical section as seen on the line 6—6 of Fig. 5.

More particularly, the pen comprises a handle 7 which is preferably of metal, and 45 is provided with a threaded shank 8 of reduced diameter. The shank 8 is bifurcated at its lower end and has arms 9 and 10 to which are attached resilient nibs 11 and 12. The arms 9 and 10 are similar in their structure and the description of one, 9, will be sufficient.

The arm 9 is rectangular in horizontal 50 cross section, and is reduced in section adjacent its end by cutting away a portion thereof to provide a shoulder 13 and a face

14 off-set from the face 15. The lower portion is reduced at the sides thereof to form a tongue 16. A lug 17 is provided on the face 14 and projects outwardly with its surface preferably flush with the surface 15. 60

The nib 11 is slotted, as indicated at 18 to receive the tongue 16. The slot extends to a point adjacent the upper wall of the lug 17. The upper portion of the nib 11 is off-set at 19 so that it will coöperate with 65 the face 14 to form a mortised joint with the lug 17 extending through the slot 18, and the tongue 16 disposed therein. The nib 11 is secured to the arm 9 by means of a set screw 20 which extends through an aperture in the upper end of nib 11, and engages a threaded bore in the arm 9. As before stated nib 12 is similarly connected to arm 10. Nibs 11 and 12 are of a form well known 70 in line pens.

Mounted upon the threaded shank 8 is a collar 21 of tubular form arranged to telescope with the handle 7, and provided adjacent its center with an inwardly extending portion 22 which is threaded to engage the 75 threads on shank 8. The collar is also enlarged exteriorly at this point and knurled to form a convenient finger grip, as indicated at 23. The lower end of collar 21 is provided with an outstanding flange 24 80 which forms a portion of a thrust bearing 85 for a slide 25.

Slide 25 is counterbored at its upper portion and provided with a thread 26. The counterbore forms a groove of sufficient diameter to receive the flange 24 and permit the collar to rotate freely with respect to the slide. A threaded thrust ring 27 engages the threads 26 and secures a flange 24 90 to the slide 25. By the construction just described the collar 21 may be rotated, thereby moving it up or down the shank without 95 rotating the slide 25.

An aperture 28 extends through the slide 25 and in opposite walls of the aperture are 100 recesses 29 and 30 within which are disposed rollers 31 and 32 respectively, thereby providing anti-friction means for movement of the nibs 11 and 12 over the walls and aperture 28.

It is obvious that by screwing the collar 21 up or down upon the shank the nibs 11 and 12 will be moved to or from each other. As the collar moves downwardly, slide 25 105 crowds the ends of the nibs 11 and 12 to- 110

ward each other. As the collar moves upward the resiliency of the nibs cause them to move away from each other, thereby changing the adjustment between the points 5 of the nibs and the breadth of the line. In order that an accurate adjustment may be made so that the same width of line may be secured each time, I have provided the handle 7 with indicia as indicated at 33, to 10 indicate the position of the collar with respect to the handle or shank 8. To get a finer adjustment I have shown upon the collar 21 lines 34 which can be registered with a mark 35 upon the handle 7, thereby giving 15 a micrometer adjustment.

What I claim is:

1. In a pen, a shank provided with threads, adjustable nibs mounted thereon

having ends inclined away from each other, a slide engaging the threads on said shank 20 having nib adjusting means swiveled thereon, said means engaged with the inclined ends of said nibs.

2. In a pen, a shank provided with threads, resilient nibs having ends inclined 25 away from each other, a slide on said shank engaging the inclined ends of said nibs for adjusting the distance therebetween, a collar rotatably secured to said slide provided with threads on its interior engaging the 30 threads on said shank.

In witness that I claim the foregoing I have hereunto subscribed my name this 23rd day of February, 1916.

FRANCIS R. GOOD.
